DESIGN FOR A DENTIST'S ANVIL

Walter O. Maitland, San Francisco, Calif.

Application March 11, 1940, Serial No. 90,828

Term of patent 14 years

To all whom it may concern:

Be it known that I, Walter O. Maitland, a citizen of the United States, residing at San Francisco, in the county of San Francisco and State of California, have invented a new, original, and ornamental Design for a Dentist's Anvil, of which the following is a specification, reference being had to the accompanying drawing, forming a part thereof.

Fig. 1 is a perspective view of a dentist's anvil showing my new design;

Fig. 2 is a side elevational view of the same;
Fig. 3 is a top plan view of the same; and
Fig. 4 is an end elevational view of the same.

I claim:

The ornamental design for a dentist's anvil, substantially as shown.

WALTER O. MAITLAND.
